(57) **CLAIM**

The ornamental design for an article of jewelry, as shown and described.

DESCRIPTION

FIG. 1 is a perspective view from the front and right side of the article of jewelry;

FIG. 2 is a perspective view from the front and left side thereof;

FIG. 3 is a top plan view thereof, the view being substantially identical regardless of what point along the circumference the article of jewelry is viewed;

FIG. 4 is a right side view thereof;

FIG. 5 is a left side view thereof;

FIG. 6 is a top plan view thereof;

FIG. 7 is a perspective view from the front and right side of a second embodiment of the article of jewelry;

FIG. 8 is a perspective view from the front and left side of FIG. 7;

FIG. 9 is a top plan view of FIG. 7, the view being substantially identical regardless of what point along the circumference the article of jewelry is viewed;

FIG. 10 is a right side view of FIG. 7;

FIG. 11 is a left side view of FIG. 7; and,

FIG. 12 is a top plan view of FIG. 7.

The dotted outline showing of diamonds arranged along the outer circumferential side of the article of jewelry in FIGS. 1-12 and the dotted outline showing of a clasp in FIGS. 1-6 is provided for environmental purposes and forms no part of the claimed design.
